(57) **CLAIM**

The ornamental design for an animal decapitation device, as shown and described.

DESCRIPTION

FIG. 1 is an environmental perspective view of an animal decapitation device showing my new design;

FIG. 2 is a front elevational view with the rear view being a mirror image thereof;

FIG. 3 is a left side elevational view thereof; and,

FIG. 4 is a right side elevational view thereof.

The broken line showing of an animal and the stand in FIG. 1 is for illustrative purposes only and forms no part of the claimed design.
